Attorney

UNITED STATES PATENT OFFICE.

DAVID STERNBERGH, OF READING, PENNSYLVANIA.

ADVERTISING-SIGN.

1,383,439.

Specification of Letters Patent.

Patented July 5, 1921.

Application filed December 29, 1919. Serial No. 347,960.

To all whom it may concern:

Be it known that I, DAVID STERNBERGH, a citizen of the United States, residing at Reading, in the county of Berks and State 5 of Pennsylvania, have invented certain new and useful Improvements in Advertising-Signs, of which the following is a specification.

My invention relates to advertising signs, 10 and my object is to attract the attention of a passer-by due to the illusion of a moving element of the sign. The invention is fully described in connection with the accompanying drawing, and the novel features are 15 pointed out in the claim.

Figure 1 indicates a preferred embodiment of my invention in connection with a pneumatic tire advertisement.

Figs. 2 and 3 are a diagrammatic elevation 20 and a diagrammatic plan view respectively, indicating the illusionary effect of my invention.

Fig. 4 indicates diagrammatically a modification.

25 While the drawings indicate the application of my idea to one article of advertisement, it of course may be readily varied to suit different articles.

In the drawing I have indicated a main 30 sign 2 which is shown in the preferred shape of a segment of a circle, and upon the outer face of which the advertising matter and a background appear; which in this case includes a path or roadway 3 along the upper 35 edge.

Spaced to the rear and located approximately at the axis of curvature of the segment of the main sign 2, is a coöperating sign 4, in this case a representation of a 40 pneumatic tire in outline, which coöperating sign is elevated sufficiently to appear as about resting on the top edge of the main sign 2 to the eye of a passing observer. This illusion is more clearly seen in Figs. 2 45 and 3, which indicate a vehicle 5 on an adjacent road, and the dotted lines representing the lines of vision. Fig. 2 indicates how the object 4 appears along the upper edge of the main sign 2, and Fig. 3 shows that the

passing vehicle gives to the observer varying 50 angles in the relation of the coöperating and main signs, so that it first appears above one end of the main sign, position *a*, and apparently travels along the top to the other end, position *b*. This illusion of motion naturally 55 attracts attention to the sign, enhancing its value, and in the preferred form indicated, the curved main sign and coöperating object sign are always in proper focus and not distorted to the eye of the passing observer. 60

Fig. 4 indicates a sign having an opening 6 through which the object behind may be seen, instead of appearing along the top edge, and it is obvious that other modifications may be readily devised. In some cases 65 a flat sign may be employed, or the curved sign might be reversed and the coöperating sign located close to the ground in front, but approximately at the axis of curvature pref- 70 erably.

By locating my improved sign at advantageous points topographically, as in a clearing in the woods, or at a curve, so as to cut off all vision except between the extreme 75 lines of vision, positions *a* and *b*, indicated in Fig. 3, a complete illusion may be obtained; and it may be designed to attract 80 pedestrians, motor vehicles, or along railroad rights of way, the traveling passengers, by proper location and elevation of the main and coöperating parts. And the obvious advantages and adaptability for a multitude of various advertised articles will be readily seen. 85

What I claim is:

A sign comprising a main board in the form of a segment of a circle and bearing the representation of a fixed background, and a coöperating board to the rear of said main board representing an object in motion, said coöperating board being located approximately at the axis of said segment and at a height to appear above the main board. 90

95 In testimony whereof I affix my signature.

DAVID STERNBERGH.
